(57) **CLAIM**

I claim the ornamental design for a self-watering planter insert, as shown and described.

DESCRIPTION

FIG. 1 is a front top perspective of one embodiment of a self-watering planter insert applied to a planter showing my new design;

FIG. 2 is a bottom perspective view thereof;

FIG. 3 is a rear top perspective view thereof;

FIG. 4 is a front view thereof;

FIG. 5 is a right side view thereof;

FIG. 6 is a left side view thereof;

FIG. 7 is a rear view thereof;

FIG. 8 is a top view thereof; and,

FIG. 9 is a bottom view thereof.

The portions of the article in broken lines are shown for illustrative purposes only and form no part of the claimed design.
